ILLUMINATED GRAB-BAR SUPPORT

Frederick Leonara Nestrock, Avon, Conn., assignor to Union Manufacturing Company, New Britain, Conn., a corporation of Connecticut

Filed May 9, 1968, Ser. No. 11,873

Term of patent 14 years

Int. Cl. D8—03

U.S. Cl. D8—235

FIG. 1 is a perspective view of an illuminated grab-bar support of my design, the broken lines being for illustrative purposes only;

FIG. 2 is an enlarged side elevation of my support;

FIG. 3 is a front elevation of the device shown in FIG. 2;

FIG. 4 is a view from above, further showing the device of FIG. 2; and

FIG. 5 is a view from below, further showing the device of FIG. 2.

I claim:

The ornamental design for an illuminated grab-bar support, substantially as shown and described.
